ATTORNEY.

WITNESS: *John Kelly*

UNITED STATES PATENT OFFICE.

BENJAMIN H. McDUFFIE, OF BROOKLYN, NEW YORK.

FAUCET.

Application filed March 28, 1921. Serial No. 456,356.

To all whom it may concern:

Be it known that I, BENJAMIN H. McDUFFIE, a citizen of the United States, residing at Brooklyn, in the county of Kings and 5 State of New York, have invented new and useful Improvements in Faucets, of which the following is a specification.

This invention relates to faucets.

More particularly the invention relates to 10 faucets for controlling and regulating the flows of different kinds of liquids which enter the device through different inlets and pass out from the device through the same outlet.

15 Some of the objects of the present invention are: to produce a faucet which may be connected to urns containing coffee and milk respectively, and with which the coffee and milk may be drawn from the urns in 20 proper proportion by manipulating a part thereof with the vessel or container to be filled; to produce a faucet including valve members which are connected to a manipulator by the use of a jointed connection; to 25 provide a faucet with a casing having a plurality of chambers, an inlet communicating with each chamber, an outlet communicating with each chamber, and valve means between the chambers and the outlet for controlling 30 the flow of liquids from the chambers. With these and other objects in view the invention resides in the particular provision, combination and relative arrangement of parts hereinafter more fully described and 35 illustrated in the accompanying drawing, in which:

Figure 1 is a central vertical sectional view through the faucet of the present invention.

40 Figure 2 is a plan view of the faucet with the cover section and the cleaning plug removed.

Figure 3 is a perspective view of the valve members and the manipulator connected 45 thereto detached from the faucet.

Figure 4 is a detail side elevation of the lower end of the faucet.

Figures 5 and 6 are perspective views of parts of the faucet detached therefrom.

50 Referring now more particularly to the drawing for details of the faucet of the present invention, it will be manifest that the same includes, a casing 10 having a cover section 11, which may be screwed onto the 55 same. The casing 10 is formed with angularly disposed walls 12 and 13 to define

chambers 14 and 15. An inlet 16 communicates with the chamber 14. An outlet 17 of the casing 10 communicates with the chambers 14 and 15 through passages 18 and 19 60 in the partition 20 which is disposed between the chambers 14 and 15 and the outlet 17. The cover section 11 has formed therewith or connected thereto an inlet extension 21 which is adapted to be preferably connected 65 to an urn having preferably milk therein. The extension 21 as shown is provided with a valve 22 for controlling the flow of the milk to the chamber 15. The inlet 16 is adapted to be connected to an urn having 70 preferably coffee therein.

Valve means is employed whereby the coffee and milk may be allowed to flow or may be stopped from flowing at will. The flow of the coffee and milk is simultaneous 75 in proper proportion, and the flow of the liquids is stopped automatically and simultaneously. The said valve means includes the passages 18 and 19. The passage 18, as shown, is larger than the passage 19 because coffee will pass through the passage 18, and of course more coffee is ordinarily desired than milk which passes through the smaller passage 19. A valve seat 23 is formed at the passage 18 on the partition 20, and a seat 24 is formed at the passage 19 on the said partition on the top side thereof. 80 valve members 25 and 26 are adapted to coact with the seats 23 and 24 respectively. The members 25 and 26 are connected to a manipulator 27. The member 25 is preferably connected to the manipulator 27 by the use of a part 28 formed on the manipulator 27, the said part 28 is screw threaded, and the member 25 has a screw threaded bore 85 thus adapting it for threading engagement with the part 28. The member 26 is preferably connected to the manipulator 27 by a part 29 which is jointed as at 30. The end section of the part 29 is screw threaded, and the member 26 has a screw threaded 90 bore thus adapting it to be threaded onto the said end section of part 29. The manipulator 27 is to be moved up and down in allowing and in cutting off the flow of coffee and milk. The manipulator moves in guide ways 31 in an annular member 32 detachably secured to the outlet end 33 of the casing 10, by a set screw 34 and a pin 35. The upper end of the member 32 has bayonet slots 100 36 for the reception of the screw 34 and the pin 35. An annular member 37 surrounds

the member 32 and is held in place thereon by a flange 38. The member 37 is cut away as at 39 at diametrically opposite points to provide shoulders 40 upon which the ends 41 of the manipulator 27 are adapted to rest when a continuous flow of the liquids is desired. The member 37 is movably and detachably related to the member 32. A finger piece 42 is secured to the member 37 to facilitate the movement of the said member in bringing the shoulders 40 into and out of the path of movement of the ends 41.

From the foregoing it should be manifest that, the device of the present invention is in fact a duplex faucet; duplex in the sense that it may be connected to two different sources of supplies of different liquids; that the liquids may be received by the faucet and may flow therefrom together in one stream in the desired proportion. It should also be manifest that the employment of the jointed connection between the manipulator 27 and the valve member 26, permits both of the members 25 and 26 to automatically and readily seat themselves, and furthermore, it allows drinking vessels such as cups and glasses to be brought into engagement with the manipulator for the filling operation without unnecessary breaking of such vessels.

In order to facilitate the cleaning of the chamber 14, the wall 12 is provided with an opening which is closed by a plug 43.

What is claimed is:

1. A faucet comprising a casing having inlets and an outlet, and valve-means between the inlets and the outlet, said valve-means including seats and gravitational members which coact with the seats, and a manipulator connected to and suspending from said gravitational members.

2. A faucet comprising a casing having chambers therein and inlets communicating with said chambers, and an outlet communicating with said chambers; and valve-means between the chambers and the outlet, said valve-means including seats and gravitational members which coact with said seats, and a manipulator connected to and suspending from said gravitational members.

3. A faucet comprising a casing having a valve controlled inlet and an outlet, valve-means between the inlet and the outlet, said valve-means including a seat and a gravitational member adapted to coact with said seat, a manipulator, and a jointed connection connecting said member with said manipulator.

4. A faucet comprising a sectional casing

having inlets and an outlet; valve-means between the inlets and the outlet, said valve-means including seats, gravitational members which coact with said seats, a manipulator connected to and suspending from said members and one of said members having jointed connection with said manipulator; and means for holding the members off of said seats.

5. A faucet comprising a sectional casing having chambers therein, an inlet communicating with each chamber, and an outlet communicating with each chamber; valve-means between the chambers and the outlet, said valve-means including seats, gravitational globular members adapted to coact with said seats, and an oscillatory manipulator connected to said gravitational globular members.

6. A faucet including a casing having a cover section, an inlet in the casing and one in the cover section, and an outlet in the casing; valve-means between the inlets and the outlet, said valve-means including seats and gravitational members which coact with the seats; means connected to the gravitational members for lifting the same, and means for holding the gravitational members off of the seats.

7. A faucet including a casing having chambers therein, an inlet in communication with each chamber, and an outlet in communication with each of said chambers, valve-means including a partition between the outlet and the inlets, seats formed on the partition, passages in the partition opening to the chambers and the outlet, gravitational members which coact with the seats to open and close said passages, an oscillatory manipulator connected to said gravitational members, the said lift members normally seating themselves on said seats; and means for holding the gravitational members off of said seats.

8. A faucet including a sectional casing having inlets and an outlet; valve-means including a partition between the inlets and the outlet and having passages therein, seats on the partition, gravitational members which coact with said seats for opening and closing said passages, and a horizontally disposed manipulator connected to said gravitational members for lifting the same and having compound movement; and means for preventing rotation of said manipulator.

In testimony whereof I hereby affix my signature.

BENJAMIN H. McDUFFIE.
